COMBINED ASH TRAY AND SERVICE LIGHT FOR RESTAURANTS OR THE LIKE

Jerome T. Miller, 2938 St. Elmo Ave. NE., Canton, Ohio

Filed Mar. 21, 1960, Ser. No. 59,798

Term of patent 14 years

(Cl. D48—20)

Figure 1 is a side elevation of a combined ash tray and service light for restaurants or the like showing my new design.

Fig. 2 is a top plan view thereof.

Fig. 3 is a side elevation thereof.

The dominant features of my design reside in the portions shown in full lines.

I claim:

The ornamental design for a combined ash tray and service light for restaurants or the like, substantially as shown and described.
